UNITED STATES PATENT OFFICE.

CHARLES A. H. SMITH, OF OAKLAND, CALIFORNIA.

KITCHEN UTENSIL.

SPECIFICATION forming part of Letters Patent No. 369,083, dated August 30, 1887.

Application filed April 7, 1887. Serial No. 234,097. (No model.)

To all whom it may concern:

Be it known that I, CHARLES A. H. SMITH, a citizen of the United States, residing at Oakland, in the county of Alameda and State of California, have invented a new and useful Kitchen Utensil, of which the following is a specification.

My invention relates to the construction of a metal can for household purposes, and has for its object the production of a device wherein several compartments—as receptacles and a number of implements employed in cooking—are combined in one utensil.

To attain this end my invention consists, essentially, in a can having a partitioned chamber for baking-powder, cream-tartar, &c., in the body or upper portion, with the usual cover at the top thereof, and a cap shutting up within a lower chamber of the can and employed as a biscuit-cutter, and also as a grater and a receptacle for nutmegs. By such a construction and combination of parts a handy and compact utensil is had for the kitchen department of households.

In the accompanying drawings, forming part of this specification, Figure 1 is a vertical section of my combined can, biscuit-cutter, nutmeg holder and grater. Fig. 2 is a bottom view of removable cap.

A is the body of the can, partitioned as at B, and forming a chamber or receptacle, C, in the upper portion for baking-powder, cream-tartar, flour, &c., with the usual cover, D,

placed over the top or upper end thereof. A separable cup or cap, E, formed of metal and provided with a flange or rim, E*, and corrugated or roughened bottom F, shuts up within the chamber G, formed by the partition-plate B in the lower end of the can. The rim of this cup or cap forms a cutter for biscuits, cake, &c., and the cup itself forms a receptacle for nutmegs. When the cup or cap is employed for a biscuit-cutter, it is removed from the bottom of the can by means of the flange or rim E* and the nutmegs displaced.

In order to prevent the material sticking within the cup or cap, an air or vent hole is made in the side or rim thereof, as shown at H.

Having thus described my invention, what I claim, and desire to secure by Letters Patent, is—

The herein-described kitchen utensil, consisting of the can-body A, having cover D, and horizontally partitioned at B to form upper and lower chambers, and the removable flanged cap E, located in the lower chamber and having a roughened bottom, F, all constructed in the manner and adapted for the purposes specified.

In testimony that I claim the foregoing I have hereunto set my hand and seal.

CHARLES A. H. SMITH. [L. S.]
